UNITED STATES PATENT OFFICE.

CHARLES A. BENNETT, OF TAUNTON, MASSACHUSETTS, ASSIGNOR TO THE BENNETT-MERWIN SILVER COMPANY, OF NEW MILFORD, CONNECTICUT, A CORPORATION OF CONNECTICUT.

DESIGN FOR A TEAPOT OR SIMILAR ARTICLE.

44,603.

Specification for Design.

Patented Sept. 2, 1913.

Application filed May 23, 1913. Serial No. 770,286. Term of patent 7 years.

To all whom it may concern:

Be it known that I, CHARLES A. BENNETT, a citizen of the United States, residing at Taunton, in the county of Bristol and Commonwealth of Massachusetts, have invented a new, original, and ornamental Design for Teapots or Similar Articles, of which the following is a specification, reference being had to the accompanying drawing, forming a part thereof.

The figure is a side view of a tea pot, showing my new design.

I claim

The ornamental design for a tea pot, or similar article, as shown.

CHARLES A. BENNETT.
